UNITED STATES PATENT OFFICE.

FRANCIS H. HAMPTON, OF SPOKANE, WASHINGTON.

FUNNEL.

Application filed May 10, 1926. Serial No. 108,108.

My present invention relates to improvements in funnels of the collapsible type and adapted for use in the performance of the functions of a siphon.

5 While the funnel of my invention is well adapted for use in many ways in filling receptacles with fluent material, it is particularly designed as an accessory for automobiles, and for this purpose the funnel is 10 fashioned with a telescoping structure which may readily be collapsed into compact form for storage when not in use, and which may with equal facility be extended for use when required.

15 The funnel is also provided with means adapting it for use as a siphon, and a hose is utilized as part of the equipment for use in filling a gasoline supply tank of an automobile. As an emergency device, the funnel 20 and its siphon features are capable of use in transferring a quantity of gasoline from one automobile tank to the tank of another automobile. Thus when a driver on the road finds that his supply of gasoline is exhausted, instead of being compelled to walk to 25 the nearest gasoline station, he may borrow a temporary supply from a generous and more fortunate driver by utilizing the funnel and its equipment for siphoning a quantity of gasoline from one tank to another.

30 The invention consists in certain novel combinations and arrangements of parts as will hereinafter be more fully set forth and claimed.

35 In the accompanying drawings I have illustrated one complete example of the physical embodiment of my invention wherein the parts are combined and arranged in accordance with the best mode I have thus far 40 devised for the practical application of the principles of my invention.

Figure 1 is a view in side elevation of a funnel embodying my invention.

Figure 2 is a vertical sectional view of the 45 telescoping funnel, showing its collapsed position by dotted lines, and also showing in dotted lines the extended hose or flexible tubing used when siphoning the fluent material or liquid.

50 Figure 3 is a top plan view, enlarged, of the funnel, with the hose coiled in its place.

The funnel is of standard shape and may be made up in standard sizes, in sectional, telescopic structure, of which 1 designates 55 the main section of inverted, frusto-conical shape, and provided with a tapering, annu-

lar flange 2 at its lower end. Within the flange 2 the section 3 is suspended, and the succeeding sections 4, 5 and 6 of successively smaller diameter and tapering in shape, 60 complete the sectional, telescopic structure of the funnel. In dotted lines Figure 2 the funnel is shown in collapsed position, and a handle 7 at the lower end of the lowermost funnel 6, is grasped to pull the successive 65 sections to the full line or extended positions of Figures 1 and 2. In collapsing the funnel the sections are successively pushed one within another in usual manner.

At approximately midway the height of 70 the main section 1 is arranged a fixed plate 8 in the form of a circular disk, and this disk, which is preferably of metal, is fashioned with a number, as four, of radiating arms 9, each of which is attached to the 75 section 1 by a rivet as 10 near its juncture with the disk or plate.

The arms extend upwardly and outwardly 80 to form flaring, spring retainers, as will be described.

In the fixed plate are formed a suitable number of ports or openings with screens 11 extended across the ports for straining or filtering the gasoline or other liquid passing through the funnel, and below the fixed 85 plate is a rotary bottom plate 12 of a diameter to freely turn within the funnel section and guided by a bolt or pin 13 which projects upwardly through an arcuate slot 14 in the fixed plate. The movable plate 90 also has a number of ports or openings 15, complementary to the ports or screened openings 11 of the fixed plate, and it will be apparent that the movable plate may be turned to closed position to shut off passage 95 of air through the screened ports and ingress of air to the interior of the funnel when it is being utilized as a siphon. During the ordinary use of the funnel, the screened ports 11 and ports 15 are of course 100 made to register for the passage of the liquid therethrough. When the device is used as a siphon, however, these ports are closed by turning the bottom plate.

At the center of the double-thick partition formed by the plates 8 and 12 is fashioned a tubular boss 16, and a suitable length of hose 17 is attached thereto by the head 18, which head fits tightly over the enlargement of the boss, and permits freedom 110 in moving the tube or hose as required.

In Figure 2 the hose or tube is shown

coiled around the inner face of the flaring wall of the main section, and retained in place by the resilient arms 9 of the fixed partition or strainer.

- 5 With the coils in place as shown the funnel may be used in the ordinary manner. When used as a siphon the screen ports of the partition are closed and the telescopic sections of the funnel are collapsed. The 10 free end of the hose is placed in the tank from which a supply of gasoline is to be taken; the funnel is closed by a finger at the bottom of the section 7, lowered to a 15 position below the level of the gasoline in the tank, and the finger remains in place while the funnel sections are being extended. The extension of the funnel starts the siphon action and the funnel is thus filled, after which its contents may be emptied into 20 the tank requiring replenishment. Other means of course may be employed for starting the siphon action to transfer, as for instance the gasoline may be transferred to a third vessel, and then poured through the 25 screened ports of the funnel into the empty tank.

Having thus fully described my invention, what I claim as new and desire to secure by Letters Patent is—

- 30 1. The combination with a sectional, telescopic funnel having a partition and screened ports, and means for closing the

ports, of a hose attached to the partition for communication with the interior of the funnel, and means for retaining the hose in 35 coiled position in the main section of the funnel.

2. The combination with a funnel having a partition with screened ports, and means for closing the ports, of a hose attached to 40 the partition for communication with the interior of the funnel, and resilient retaining arms for holding the hose in coiled position above the partition.

3. The combination with a funnel having 45 a partition and screened ports therein, and a rotatable, ported closure for said screened ports, of a hose attached to the partition for communication with the interior of the funnel, resilient retaining arms on the partition 50 for the coiled hose, and means for fastening said arms to the funnel.

4. The combination with a telescopic funnel having a partition and screened ports 55 therein, a rotatable ported disk-closure having a guide pin for engagement with a slot in the partition, and an open boss on the partition, of a hose attached to said boss, resilient retaining arms on the partition for the coiled hose, and means for fastening 60 said arms to the funnel.

In testimony whereof I affix my signature.

FRANCIS H. HAMPTON.
